UNITED STATES PATENT OFFICE

105,870

DESIGN FOR A UNIT HEATER CASING

Theodore Hess, Prairie View, Ill., and Charles T. Perkins, Racine, Wis., assignors to Modine Manufacturing Company, Racine, Wis., a corporation of Wisconsin

Application July 14, 1937, Serial No. 70,428

Term of patent 14 years

To all whom it may concern:

Be it known that we, Theodore Hess and Charles T. Perkins, both citizens of the United States, residing at Prairie View, in the county of Lake and State of Illinois, and Racine, in the county of Racine and State of Wisconsin, respectively, have jointly invented a new, original, and ornamental Design for a Unit Heater Casing, of which the following is a specification, reference being had to the accompanying drawing, forming a part thereof.

Referring to the drawing:

Fig. 1 is a perspective view of a unit heater casing embodying our design, the narrow vertical side of the case not shown being like the narrow side shown in the drawing; and

Fig. 2 is an elevational view of the rear side of the unit heater casing shown in Fig. 1.

We claim:

The ornamental design for a unit heater casing, as shown, and described.

THEODORE HESS.
CHARLES T. PERKINS.
